CLAIM

The ornamental design for a wrist guard, as shown and described.

DESCRIPTION

FIG. 1 is a top, rear and right side perspective view of the wrist guard of the invention shown in use of a wearer's hand;

FIG. 2 is a bottom, rear and right side perspective view thereof shown in use on a wearer's hand;

FIG. 3 is a top plan view thereof;

FIG. 4 is a bottom plan view thereof;

FIG. 5 is a right side elevational view thereof;

FIG. 6 is a left side elevation view thereof;

FIG. 7 is a front elevation view thereof; and,

FIG. 8 is a rear elevation view thereof.

The broken line showing of a wearer's hand is for illustrative purposes only and forms no part of the claimed design.

FIG. 1

FIG. 2

FIG. 4

FIG. 3

FIG. 5

FIG. 6

FIG. 7

FIG. 8
